J. P. FLETCHER

STERILIZER

Filed July 8, 1922

Inventor

John P. Fletcher.

UNITED STATES PATENT OFFICE.

JOHN P. FLETCHER, OF CARLISLE, PENNSYLVANIA.

STERILIZER.

Application filed July 8, 1922. Serial No. 573,678.

To all whom it may concern:

Be it known that I, JOHN P. FLETCHER, a citizen of the United States, and a resident of Carlisle, in the county of Cumberland and State of Pennsylvania, have invented a new and useful Improvement in a Sterilizer, of which the following description, in conjunction with the accompanying drawings, is a specification.

10 This invention generically relates to surgical appliances, more specifically it is directed to an emergency sterilizer for needles and solutions used in the administration of hypodermics.

15 The fundamental purpose of this invention is to produce a sterilizer of the type indicated having characteristics rendering it especially efficacious for army field usage.

Another important object of this invention is to effect an inexpensive, compact and efficient sterilizer which may be readily utilized in the field to sterilize hypodermic solutions or needles irrespective of prevailing weather conditions.

25 Other important objects of this invention are to effect a sterilizer having facilities to prevent leakage of the fuel as well as one which is durable and of the least possible dimensions to permit convenient packing in the medical kit or portage in the pocket of the operator depending upon the exigency of the situation.

With these and other objects in view my invention consists in certain novel details 35 of construction, combination and arrangement of parts to be more specifically hereinafter set forth and claimed.

Briefly stated this invention embodies an open ended rectangular metallic casing having a hinged wall, a trough arranged transverse of the open end of the casing, an alcohol burner situated beneath the trough in the lower part of the casing and a cap closing the open end of the casing and simultaneously functioning to retain the hinged wall in its normal or closed position.

In the accompanying drawings in which corresponding parts are indicated by similar characters:

50 Figure 1 is a transverse vertical section partly in elevation of the sterilizer assembly, the top and hinged wall being shown in open position.

55 Figure 2 is a transverse vertical section partly in elevation showing the arrange-

ment and construction of the alcohol burner, and.

Figure 3 is a top plan view of the burner collar.

The prevailing army practice in the administration of hypodermics has been to sterilize the hypodermic needles or solutions by means of a teaspoon, tablespoon or miniature tray held above a small glass alcohol burner. While this procedure meets the requirements of the hospital ward and may be employed under normal conditions, it is manifestly highly unsuited to field service wherein not infrequently the fuel is lost by leakage or otherwise as the sterilizer is conveyed from patient to patient, or the flame extinguished at the most inopportune time by the wind. It is therefore the aim and purpose of this invention to provide a simple compact sterilizer which will overcome these defects and materially aid in the administration of hypodermics under emergency field conditions.

In the illustrated embodiment characterizing this invention there is shown a metallic casing (1) rectangular in configuration and having bottom (2), side walls (3), rear walls (4) and a front wall (5) hinged as at (6).

Front wall (5) is formed with a peripheral flange (7) which when the wall is in its normal or closed position overlies the sides and upper extremities of walls (3). By hinging the wall (5) and providing the peripheral flange aforesaid it may be used as a tray for any purpose desired, while at the same time permitting ready removal of the alcohol burner as will be obvious without further discussion.

Front wall (5) is hinged as at (9) to the rear wall (4) and formed with a peripheral flange (10) so that when the cap (8) is in its normal position it not only closes the open end of the casing but also engages the free extremity of hinged wall (5) and securely retains the latter in closed position.

The cap (8) is hinged as at (9) to the rear wall (4) and formed with a peripheral flange (10) so that when the cap (8) is in its normal position it not only closes the open end of the casing but also engages the free extremity of hinged wall (5) and securely retains the latter in closed position. To accommodate the hypodermic needles or solutions to be sterilized, a trough (11), U-shaped in cross-section and holding about 5 c. c. of solution, is arranged transverse of the open end of the casing between the extremities of walls (3). This arrangement causes the flame from the burner, hereinafter to be mentioned, to pass on each side of the trough, thus increasing the

heated surface of the trough and expediting heating of its contents.

Within the lower part of the casing immediately below and in suitable heating relation with respect to the trough (11) is disposed an alcohol lamp or burner (12) dimensioned to snugly fit within the casing. To prevent movement of the burner within the casing brackets (12) are attached to the walls of the casing so as to overlie the upper edge of the container as clearly shown in Figure (1) of the drawing.

Burner (12) consists of a rectangular metallic fuel container having bottom (14), side walls (13) and top (15), provided with an opening (16). Surrounding the opening (16) is an externally threaded collar (17) having a bore (18) which is reduced at a point slightly below the upper extremity of 20 the collar to afford a seat (19).

A wick holder (20) bearing wick (21) is positioned in the bore (18) which latter at equally distant points is formed with a series of V-shaped grooves (23) communicating with the exterior of the container.

These grooves (23) form passages through which the products of volatilization may pass to the flame, thus furnishing an additional fuel supply which otherwise 30 would be lost.

Normally the pressure exerted by the volatilization causes an overflow of the fuel and an undesirable spreading of the flame, both of which defects are eliminated by provision of the passages aforesaid.

To prevent leakage of the fuel a cap (24) is threaded on collar (16), the lower edge of the collar bearing against a suitable washer (25).

40 In the use of this sterilizer the top and front walls are brought to position shown in Figure (1), the trough filled with the solution to be sterilized and the burner ignited. After the hypodermic needles or solution have been sterilized and it is desired 45 to convey the sterilizer to another location or place in the medical kit, the burner cap is positioned on the burner, the hinged wall (5) folded upwardly and the cap (8) down-

wardly to close the open end of the casing 50 and at the same time engage the upper extremity of the hinged wall to retain the same in its normal enclosed position.

In conclusion it will be seen that the above structure provides a sterilizer which is simple, compact and especially adapted to the need for which it is designed.

Although in the foregoing certain elements have been specified as best adapted to perform functions allotted to them, nevertheless it is to be understood that various minor structural changes may be resorted to within the scope of the appended claims without departing from or sacrificing any of the principles of this invention.

Having defined my invention, what I claim as new and wish to secure by Letters Patent is:

1. A sterilizer comprising a casing open at its upper end and including rear and side walls, a hinged section normally forming a closure for the open side of the casing, a burner removably secured within the lower portion of the casing, a sterilizing trough in the open end of the casing and a cap fitting said open end and providing a closure for the latter, and the trough, said cap at the same time securing the hinged section in its normal position.

2. A sterilizer comprising a casing open at its upper end and including rear and side walls, a hinged section normally forming a closure for the open side of the casing, said section being formed along its side and front edges with up-standing flanges to provide a tray when said section is lowered to a horizontal position, a burner removably secured within the lower portion of the casing, a sterilizing trough disposed central of the open end of the casing with its extremities affixed to the side walls thereof, to permit the flame to pass on each side of the trough and expedite heating of its contents, and a cap closing the open end of the casing and the trough, said cap at the same time securing the hinged section in normal position.

JOHN P. FLETCHER.
